W. R. WATROUS

SORTING CHUTE

Filed July 11, 1923

UNITED STATES PATENT OFFICE.

WILLIAM R. WATROUS, OF CHESTER, CONNECTICUT, ASSIGNOR TO C. J. BATES & SON, OF CHESTER, CONNECTICUT, A FIRM COMPOSED OF CARLTON J. BATES AND HAMILTON C. BATES.

SORTING CHUTE.

Application filed July 11, 1923. Serial No. 650,854.

To all whom it may concern:

Be it known that I, WILLIAM R. WATROUS, a citizen of the United States, residing at Chester, in the county of Middlesex and State of Connecticut, have invented a new and useful Improvement in Sorting Chutes; and I do hereby declare the following, when taken in connection with the accompanying drawings and the characters of reference 10 marked thereon, to be a full, clear, and exact description of the same, and which said drawings constitute part of this application, and represent, in—

Fig. 1, a side view, partly in section, of 15 a sorting chute constructed in accordance with my invention.

Fig. 2, a transverse sectional view thereof.

Fig. 3, a similar view, showing the mouth provided with turning-shoulders.

20 This invention relates to improvement in sorting chutes particularly adapted for use in connection with machines for forming blanks for crochet hooks, stilettos, manicure sticks, and other articles which are tapered, 25 and hence heavier at one end than the other. In forming articles of this general type, it is necessary that they should all be presented to the operating mechanism with the points in the same direction, and the object of this 30 invention is to provide a chute by which the blanks will be delivered in proper position, and the invention consists in the construction as hereinafter described and particularly recited in the claims.

35 In carrying out my invention, I employ a chute 5, with a tapered mouth 6 substantially rectangular in cross-section but wider than the diameter of the chute. Transversely across the top of the mouth is a balancing bar 7 having an upper sharp edge 8. Blanks 9, which have been previously cut 40 into desired form and larger at one end than the other, are delivered to the chute by any suitable conveyor, herein represented by a belt-conveyor 10 having hooks 11 which sup-

port the ends of the blank and discharge them into the chute onto the edge of the bar 7. The side of the chute adjacent to the conveyor may be flared outward and formed with clearance-notches 13, through which 50 the hooks 11 will pass. The ends of the chute are formed with inset shoulders 12. When the blank is delivered by the conveyor, or has been placed upon the bar 7, the heavy end will drop downward and strike one of 55 the shoulders 12, and will rest on that shoulder while the smaller end falls downward into the chute 5, so that all the blanks will be presented smaller end downward.

On the other hand, if the blanks are to 60 be presented large end downward, the shoulders 12 will be omitted, as shown in Fig. 3 of the drawings, so that the blanks delivered to the bar 7 will fall, large end downward, and hence pass into the chute 5 in 65 that position. This insures the proper presentation of the blank to suitable mechanism for further operations.

I claim:

1. A sorting chute, provided with a mouth 70 wider than the diameter of the chute, and a fixed transverse bar across the center at the upper end of the mouth.

2. A sorting chute, having a mouth wider than the diameter of the chute, and a fixed 75 transverse bar extending across the center at the upper end thereof, and having a sharp upper edge.

3. A sorting chute, having a mouth wider than the diameter of the chute, a fixed transverse bar at the center of the upper end of the mouth, said mouth provided at opposite 80 ends, below said bar, with shoulders.

In testimony whereof, I have signed this specification in the presence of two subscribing 85 witnesses.

WM. R. WATROUS.

Witnesses:

S. R. CHARD,
C. C. COLTON.
